UNITED STATES PATENT OFFICE.

LOUIS M. SEVERSON AND ALFRED LIVINGSTON, OF CHICAGO, ILLINOIS.

PERFORATED MUSIC ROLL.

1,411,306.

Specification of Letters Patent.

Patented Apr. 4, 1922.

Application filed March 14, 1921. Serial No. 452,260.

To all whom it may concern:

Be it known that we, LOUIS M. SEVERSON and ALFRED LIVINGSTON, citizens of the United States, residing at Chicago, in the county of Cook and State of Illinois, have invented certain new and useful Improvements in Perforated Music Rolls; and we do hereby declare the following to be a full, clear, and exact description of the same, 10 reference being had to the accompanying drawings, forming part of this specification.

This invention relates to a perforated music roll for use on automatic player 15 pianos, and has for its object the provision of a sheet so punched and printed that each syllable of the printed matter shall exactly register with the corresponding note perforation punched in the sheet at a previous 20 time by a different machine.

In making music rolls it is customary to run a pack consisting usually of from fifteen to eighteen sheets through a machine quite similar in construction and operation to an ordinary multiple punch press, this punch perforating the sheets in the well known manner, so that a plurality of the punch holes merge, thus forming 25 slots. After the sheets of the pack have 30 been so punched, the sheets are separately run through a stenciling machine or a printing machine in order to place the words of the music on the edge of the roll.

This method is satisfactory only in a fair 35 measure, since it has been impossible up to the present time to secure accuracy in the placing of the words or syllables at the two ends of the roll, for the reason that, if the words or syllables are made to correspond 40 with the music perforations at the beginning of the piece, they will be found to be out of registry at the close of the piece. By bringing the center of the roll into correct registry with the stencil, the error may 45 be reduced fifty per cent. at either end, but, even in this case, the error is large enough to be decidedly appreciable when singing with the player piano.

There are many conditions which co-operate 50 to form this lack of registry, the three principal ones being (a) the contraction and expansion of the individual sheets due to change of temperature or relative humidity, thus altering the moisture content 55 of the paper; (b) the slippage of the pack while it is being fed through the multiple

punch press; and (c) the variation of the rollers or pullers that feed the pack through the multiple punching machines.

Whatever the cause may be, it has been 60 found that the lengths of these perforated rolls, which are usually from eighteen to twenty-five feet in length, vary to a considerable extent in spite of the fact that they are made from the same master and 65 under conditions as near similar as it is possible to have in practice. The printing machine or stencil is naturally quite constant and unchanging in operation, so that when these rolls of various lengths are 70 printed they are found to be out of lateral alignment with the corresponding notes or perforations at either or both ends.

In the practice of making sheets of the present invention, no attempt is made, as 75 previously, to avoid the varying length of the perforated rolls, but the words or syllables are brought into accurate synchronization and alignment with the music expressed by the perforations by an intermittent printing and by a shifting of the perforated music sheet to correct registry just before each impression is made.

In preparing the master which is laid off in steps of progression, a perforation in the 80 margin of the roll is placed after every certain number of steps. When this master is run through the multiple punch press machine, this marginal perforation in the master sheet also cuts a perforation on one 85 or both margins of the roll, as may be desired, the result being that although the rolls may vary in length to any degree within usual practice, each side marginal perforation will nevertheless always be in lateral alignment with the adjacent music perforations throughout the entire roll, since the distance between the marginal perforations is but a small fraction of the width 90 or length of the roll.

In printing the syllables corresponding 95 to the notes on these perforated rolls, each roll or sheet is advanced through the printing machine intermittently a little over an inch at a time, by means of these holes 100 placed in the margin of the roll. It is to be noted that the holes in the margin nearest the printing or stenciling member invariably position the sheet while the holes in the other margin are used only to aid in 105 moving the sheet forward and do not locate the sheet with respect to the addressograph

machine which prints the words. It is preferable that the holes on either margin be staggered with relation to the holes in the opposite margin and since the holes in each margin are spaced about three inches apart the longitudinal distance between consecutive (but not adjacent) perforations will be but an inch and a half.

The mechanism by which the rolls are produced forms no part of the present invention so the printing device may be of any of the types now used for this work such as an addressograph machine and is preferably one that prints, stencils, or marks about three inches at each impression. Each roll of the same composition naturally has the same number of side perforations, so that each roll or sheet will receive the same number of impressions and each impression will be located in proper alinement and synchronization with the perforated music notes corresponding to the syllables included in the impression, this result being accomplished by automatically synchronizing the sheet pulling or tracking device with the regularly timed printing mechanism.

It will be seen that the novel feature of the process is the method of synchronizing the printed or stenciled syllables with the corresponding notes on a perforated music roll by having the marginal holes, made at the time the sheets are perforated, govern the shifting forward and backward, as the case may be, of the sheet, so that the various impressions of the printing or stenciling mechanism shall be accurately registered with the music perforations. The invention is to be considered as limited only by the claims hereinafter, however, the mechanism shown in the figures being purely illustrative.

In the drawings,—

Figure 1 is a plan view of one form of the device which can be used for making a roll of our invention.

Fig. 2 is a side elevation thereof.

Fig. 3 is an end view.

In the drawings, 10 is a table supported by the usual legs 11 and slotted as at 12 to receive a pair of connected tracking or positioning wheels 14 each carrying a plurality of tapered pins 15 properly staggered on the two wheels so as to correspond with the marginal perforations 16 of the music roll 17. The pins 15 of the wheel 14, which is located near the printing or stenciling mechanism, locate or position the sheet with respect to such printing mechanism, while the pins 15 of the wheel 14 at the other end 60 of the shaft 18 engage the sheet to advance it at the time between its engagement with successive pins 15 of the positioning wheel 14, and for this reason the pins of wheels 14 are preferably staggered.

These wheels 14 are each keyed to a shaft

18 supported in depending journals 19 and 20 supported from the table 10. The shaft 18 extends through the bearing 20 beyond which it carries a sheave pulley tension wheel 21 and a ratchet wheel 22, the latter 70 being driven by means of a pawl 23 carried on a rocking arm 24 which furnishes the intermittent motion given to the shaft 18.

A drive shaft 25 carries at one end a wheel or crank 26 having a pin 27 which is fitted 75 into a pitman 28 pivoted to one end of a lever 29 and slotted as at 30 to receive a pin 31 carried by the printing mechanism crank arm 32 which is pivoted as at 33 to the base or table 10. The lever arm 29 is connected 80 to a similar lever arm 36 by means of a shaft 37 supported in bearings 38 rising from the table. A link 39 pivoted to the free end of the lever 36 is connected to the rocking arm 24 at a point about midway between its hub 85 and the pawl 23 which drives the ratchet wheel 22.

A pawl 40 pivoted to the table 10 operates by gravity to hold the ratchet wheel 22, and hence the shaft 18, stationary against the 90 action of the coiled spring 41 which is connected to a belt 42 lying in the groove of the sheave pulley tension wheel 21, so as to urge the wheel in a counterclockwise direction, as seen in Fig. 2, the necessary resilience being provided by a second spring 43 secured to the belt 42 and to a lug 44 depending from the table 10, to which lug is also secured the free end of the spring 41. The throw of the rocking arm 24, by virtue 100 of the relative lengths of the levers 29 and 36, is such as to cause the ratchet wheel 22 to slightly overrun the pawl 40, but when the link 39 is descending with the now inactive pawl 23, the coiled spring 41 will act to 105 draw the ratchet wheel 22 into firm contact with the stop pawl 40 and will hold the appropriate conical pin 15 exactly centrally of the slot 12.

It will be noted that the number of ratchet teeth is the same as the number of pins 15 on either of the tracking wheels 14 or, in other words, the number of ratchet teeth corresponds to the total number of positioning pins and the pawl 40 is so located 115 that during each dwell of the intermittent mechanism a single positioning pin will be vertically above the shaft 18, and on the next reciprocation of the rocking arm the next adjacent pin on the same tracking wheel 120 will be similarly located.

The printing head is diagrammatically illustrated at 45 and is secured to an arm 46 forming with the arm 32 a bell crank lever pivoted just below the table at 33. 125 The impression stroke is timed to take place while the tracking wheels are still, and since this printing mechanism is preferably regularly timed, receiving its motion from the crank 26 and pitman 28, the pushing pawl 130

23 is caused to recede slightly past the next successive ratchet tooth to the rear in order to provide sufficient lost motion to insure the raising of the type or stencil from the paper before the tracker wheels start to advance the roll.

The record roll sheets are punched in packs, as stated, the music perforations being formed by a plurality of punch holes varying from single circular holes to long slots made of a hundred or more overlapped holes, while the marginal perforations are each single holes spaced about seventy steps of progression of the sheets apart on each margin, so that the sheets or rolls will advance thirty-five times between the punching of successive opposite marginal perforations. It is preferable to punch a half dozen or so marginal perforations at either end of the rolls beyond the notes corresponding to the words, in order to permit the advancing of the sheets a number of times before the first impression, but this is not at all essential.

25 When the pack of sheets is punched the rolls are fed separately to the mechanism illustrated. It will be understood that the rolls are delivered to the printer reversed, so that the rolls, when printed, may be wound directly upon the cores or spools in finished form, except for the ring-holding tabs which are later affixed to the pointed front tip of the roll, and that only such mechanism is shown as is thought necessary to illustrate the practice of the process, all other mechanism being omitted for the sake of clearness and to emphasize the fact that the invention lies particularly in the process itself, rather than in the specific embodiment of any particular printing and advancing means.

The shaft 25 rotates at constant speed and, therefore, operates the printing head 45 at a definite number of reciprocations per minute by virtue of the slot and pin connection with the pitman 28. The pitman, thus operated, constantly and regularly rocks the levers 29 and 36 and through the link 39 and the pushing pawl 23 intermittently operates the tracker wheels 14 to advance the sheet or roll, but acts in such a manner that the pawl 23 overruns its dwell position to an extent equal to the greatest possible variation in the spacing of successive perforations 16 in the side margins of the perforated roll, in order to insure that the conical pin shall properly engage the corresponding hole 16 on its forward movement and carry the slack in the roll slightly beyond the printing position. The spring 41 now returns the tracker wheels 14 and consequently the appropriate pin 15 to proper position, this

action causing a shifting of the record sheet 17 to correct registry with the printing mechanism, irrespective of the shrinkage or expansion of the sheet. The spring 41 cooperates with the pawl 40 to hold the tracker wheels 14 in definite position during the downward movement of the link 39 which takes place simultaneously with the downward movement of the printing head 45 which prints the syllables. It will be noted that the tracking mechanism is stationary during the printing and that for a slight period just before, immediately after, and during the impression stroke the position of the slack in the record sheet 17 is controlled absolutely and solely by a single pin 15 exactly fitting a marginal perforation 16, thus securing absolutely accurate registry of the adjacent syllables with the corresponding music perforations, since the latter necessarily register with the marginal perforations, irrespective of the shrinkage, slippage, etc.

The foregoing description of the preferred mechanism is purely illustrative and is not to be considered as limiting the scope of the invention in any way or to narrow the meanings of the words of the following claims which define such invention.

What we claim is:

1. A music roll having a central longitudinal portion perforated to form slots and having a series of substantially equispaced marginal perforations, and syllables arranged in longitudinal series along a margin of said roll each of said syllables being definitely spaced with respect to a proximate marginal perforation.

2. A music roll sheet having a central longitudinal series of perforations therein and a second series of perforations along one edge thereof, said second series consisting of a plurality of substantially equispaced single holes, each in definite relation to proximate irregular central perforations, and syllables arranged in a longitudinal series on said sheet, the syllables nearest each of said single holes being definitely spaced with relation thereto and therefore definitely located with respect to the central perforation representing that syllable.

3. A music roll sheet having its central longitudinal portion slotted to form note making perforations and having a series of additional registering perforations and syllables on said sheet located in groups each group being positioned with respect to a proximate registering perforation irrespective to the location of other groups.

LOUIS M. SEVERSON.
ALFRED LIVINGSTON.
